UNITED STATES PATENT OFFICE

CHARLES D. DALLAS, OF CHICAGO, ILLINOIS

COILING MACHINE

Application filed January 14, 1929. Serial No. 332,366.

My invention relates to coiling machines, and more particularly it relates to machines adapted to impart curvature to strips of material as a result of their being fed 5 through the machine, the strips being discharged so as to coil about themselves in accordance with the degree of curvature imparted to the sheet.

Such sheets are coiled for advantageous handling in annealing or other processes in which it is desirable that the coil be formed with the contiguous windings spaced apart sufficiently to permit free circulation of heated air therebetween, and one of the objects of the invention is the provision of an improved coiling machine adapted to impart the desired curvature and windings to strips of material fed therethrough to so shape the sheet at predetermined intervals as to prevent the contiguous windings of the sheet from packing so closely as to prevent free circulation of air between the windings.

It is found in practice that the windings do not always space themselves uniformly 25 and that contiguous windings are frequently too close in some portions to permit of free circulation of heated air and it is another object of the invention to provide transversely extending corrugated sections of sharper curvature than the intervening sections which form spacers providing uniform spacing between contiguous windings.

Another object of the invention is to provide a device of the class described which 35 is simple in construction, easily manipulated and can be manufactured at a minimum cost.

Many other objects and advantages of the 40 construction herein shown and described will be obvious to those skilled in the art from the disclosure herein given.

To this end my invention consists in the 45 novel construction, arrangement and combination of parts herein shown and described, and more particularly pointed out in the claims.

In the drawings wherein like reference 50 characters indicate like or corresponding parts;

Fig. 1 is a plan view of a device embodying my invention:

Fig. 2 is an end elevational view of the device:

Fig. 3 is a section along the line 3—3 of 55 Fig. 1:

Fig. 4 is a view of one of the rollers forming a portion of the device drawn to a larger scale:

Fig. 5 is a view along the line 5—5 of 60 Fig. 4 drawn to a larger scale: and

Fig. 6 is a detail view showing the relationship of the contiguous windings of the coil of material after being subjected to the operation produced by the device of my 65 invention.

The device is illustrated in connection with a three roll coiling machine, the details of which are described only for illustrating the operation of my device and without intending to claim any of the three roll features which are known to be old in the art.

Referring now to the drawings forming part of this specification, the numeral 10 generally designates a frame having upright 75 end portions 11 and 12 forming a roller housing. Slidable bearings 20 provide a mounting for an upper roller 14. The bearings 20 are adjustably held in fixed position by means of rods 21. The rods 21 have 80 threaded connections with the bearings 20 which permit the spacing to be varied between the roller 14 and a pair of underlying rollers 15 and 16. The rollers 14, 15, and 16 are operatively connected by means of a plurality of gears, the operation and interconnection of which are hereinafter more particularly described. The rollers 15 and 16 are spaced transversely sufficiently to permit the placing therebetween of the lower 90 portion of the upper roller 14 so that a plate travelling between the upper and the lower rollers has an upward curvature imparted thereto, the degree of curvature being dependent upon the spacing of the rollers and 95 the thickness of material. The adjustability of the bearings 20 adapts the device for curving and winding material sheets of different thicknesses and also to vary the degree of curvature imparted to the sheets when fed 100

between the roller 14 and the rollers 15 and 16.

The threaded rods 21 are rotated for adjustment of the bearings 20 by manually operated mechanism which includes a wheel 31 having a handle 32. The wheel 31 is rigidly connected to a shaft 28 which extends the full width of the device. Each end of the shaft 28 is provided with a worm drive 27 which suitably engages a corresponding gear 26. Sleeves 38 provide mountings for vertically extending rods 25 to which the gears 26 are fastened. Gears 23 suitably fastened to the upper ends of the rods 25 operatively engage gears 22 which are fixedly mounted upon the threaded rods 21. By rotating the wheel 31 the operator will thus actuate the intervening mechanism to raise and lower the adjustable bearings 20 as desired.

For the purpose of determining the amount of shift of the bearings 20 and controlling the resultant degree of curvature, etc., to which the sheets of material fed therethrough are subjected, I have provided a gauge rod 30 which is suitably graduated for the purposes mentioned. A pointer 29 is mounted on the threaded portion of the shaft 28 and held against rotation with the shaft. When the shaft 28 is rotated by actuating the wheel 31 the pointer 29 moves longitudinally of the shaft by reason of its threaded connection therewith. The movement of the pointer member 29 relative to the rod 30 indicates the amount of shift of the bearing members 20.

The upper portion of the frame 10 provides a bracket 33 upon which a coil support plate 35 is mounted by means of rivets or bolts 34. In feeding the sheet of material between the upper roller 14 and the lower rollers 15 and 16 the sheet turns upwardly and coils about itself, being assisted in its initial coiling by the position and the curvature of the plate 35. The plate 35 and a pair of rollers 13 form a support for the self wound portion of the sheet as rapidly as it is fed through the device.

The closer the roller 14 is positioned to the rollers 15 and 16 the sharper will be the curvature imparted to the sheet of material being fed therebetween. It is the purpose of the invention to provide intermittent sharply curved portions separated by predetermined lengths less sharply curved portions serving as spacers which keep the contiguous windings separated. The same result would be obtained by the operator using a wrench on the rod 21 to suddenly raise and lower the roller 14. This would, however, require the constant attention of the operator and my invention provides for securing the same results automatically by mounting one or more horizontal bars 40 on one of the rollers, preferably the roller 14.

The bars 40 are inset in grooves 55 in the roller 14 and fastened by screw bolts 42. Any number of grooves 55 can be provided for bars 40. Filler bars 41 are placed in the intermediate grooves if it is desired to increase the spacing between the bars 40. The bars 40 project outwardly and produce a short section of sharply curved material as they are brought into contact with the sheet by rotation of the roller 14 in the same manner as if the roller had been suddenly lowered or a roller of larger diameter substituted for the roller 14. The bars 40 form a ridge on the otherwise continuous curved periphery of the roller 14. The bars 41 have their outer exposed surface conforming to the periphery of the roller.

Upon feeding a sheet of material 45 through the device, each of these projecting bars 40 form a corresponding transverse corrugation 56 in the sheet. The corrugations 56 prevent close packing of the contiguous windings comprising the coil thus automatically resulting from the curvature imparted to the sheet.

Any desired number of bars 40 and 41 may be provided, the number and spacing of which depend upon the closeness of the spacing required for the corrugations 56 in the coiled sheet. I have shown three bars 40 equally spaced about the periphery of the roller 14. In order that the same roller 14 may be utilized for a variety of spacings, it may be provided with a maximum number of grooves each suitable to receive either a bar 40 or a filler bar 41. Bars 40 are mounted in such of the grooves as correspond to the spacing of the corrugations desired for the particular material being coiled. The intermediate grooves each have a filler bar 41 mounted therein so that the intervening spaces between the projecting bars 40 present a smooth surface and impart a uniform curvature to the sheet between the corrugations 56. In Fig. 5 I have shown only one of such bars 41 but it is obvious that any desired number of such bars may be inserted in corresponding grooves provided for that purpose.

Any desired mechanism may be utilized to drive the device, that shown and described being only typical and does not form a part of the invention. A shaft 43 extending through the frame 10 is operatively connected with any source of power (not shown). A gear 17 is mounted on the shaft 43 to mesh with gears 18 and 19 mounted on the rollers 15 and 16, respectively. Rotation of the shaft 43 causes the rollers 15 and 16 to rotate in a direction to advance a sheet of material being fed thereover.

Since the upper corrugating roller 14 is adjustable relative to the rollers 15 and 16 I have provided it with a driving gear 46 positioned to mesh with an idler gear 47.

for any desired shifting of the roller. An idler gear 48 operatively connects gear 47 with gear 19. The system of gears thus shown provides for advancing a sheet of material forwardly between upper corrugating roller 14 and the lower rollers 15 and 16.

The rollers 13 forming a support for the coiled portion of the sheet are driven by a sprocket chain drive 49. For this purpose a sprocket wheel 50 is mounted on the near end of each of the rollers 13, as observed in Fig. 2. A sprocket wheel 51 suitably mounted on the roller 16 is operatively connected with the sprocket wheel 50 by the chain 49.

The operation of the device will be obvious to those familiar with the art. The sheet of material 55 is positioned with one end in engagement with the rollers 14 and 16, whereby it is fed between the rollers and given the desired degree of curvature. The forward end of the sheet turns upward in accordance with the degree of curvature imparted to the sheet by the rollers 14, 15 and 16. As the sheet 55 advances, the forward end travels upwardly and rearwardly and curves about itself sufficiently to complete a winding which rests upon the rollers 13. The continued travel of the sheet 55 causes the coiled portion to revolve and wrap about itself forming additional windings. This coiling process is assisted by the rotation of the rollers 13. As the coil increases in size, the support plate 35 assists in retaining the coil in position on top of the device. The plate 25 serves the further purpose, in the case of relatively thick sheets of material or sheets having a large radius of curvature of guiding the forward end of the sheet downwardly to assist in forming the initial inner winding.

Thus, it will be seen, that I have provided a device of the class described which is operable to impart permanent curvature to flat sheets of material and to permit the curved portion to coil about itself in accordance with the degree of curvature and to simultaneously form transversely extending corrugations in said sheet which prevent close packing of any of the contiguous windings.

Having thus described my invention, it is obvious that various immaterial modifications may be made in the same without departing from the spirit of my invention, hence I do not wish to be understood as limiting myself to the exact form, construction, arrangement and combination of parts herein shown and described, or uses mentioned.

What I claim as new and desire to secure by Letters Patent is:

1. In a coiling machine of the class described, a plurality of rollers operable to curve a sheet of material fed therethrough,

one of said rollers having a plurality of longitudinally extending sockets, bars mounted in selected ones of said sockets to form longitudinal ridges on said roller and filler bars mounted in the intermediate sockets having their exposed faces continuous with the peripheral surface of said roller.

2. In a coiling machine of the class described, a plurality of rollers suitably positioned to impart a predetermined curvature to a sheet of material fed therebetween, adjustable mounting for one of said rollers operable to vary the effective space between the rollers, one of said rollers having a plurality of longitudinally extending sockets with bars mounted in certain of said sockets forming longitudinal ridges on said roller and filler bars mounted in others of said sockets having their exposed faces of the same curvature and continuous with the outer peripheral surface of said roller.

3. In a coiling machine, a plurality of rollers suitably positioned to curve a flat sheet of material fed therethrough, driving means for said rollers, adjustable mountings for said rollers operable to vary the curvature imparted to said sheets, one of said rollers having a plurality of longitudinally extending sockets, bars mounted in certain of said sockets forming longitudinal ridges on said roller, filler bars mounted in others of said sockets having their exposed faces of the same curvature and continuous with the outer peripheral surface of said roller, and a support suitably positioned to receive said sheet as it is discharged from said rollers and to permit the sheet to wind about itself to form a coil.

4. In a coiling machine, a plurality of rollers suitably positioned to curve a flat sheet of material fed therethrough, driving means for said rollers, adjustable mountings for said rollers operable to vary the curvature imparted to said sheets, one of said rollers having a plurality of longitudinally extending sockets, bars mounted in certain of said sockets forming longitudinal ridges on said roller, filler bars mounted in others of said sockets having their exposed faces of the same curvature and continuous with the outer peripheral surface of said roller, supporting members suitably positioned to receive the sheet as it is discharged from the rollers and to permit the sheet to wind about itself to form a coil, and rollers operable to assist said winding operation.

In witness whereof, I hereunto subscribe my name this 10th day of January, A. D. 1929.

CHARLES D. DALLAS.
